UNITED STATES PATENT OFFICE

138,288

DESIGN FOR A PROJECTILE

Norman W. La Clair, Forest Lake, Minn.

Application October 25, 1943, Serial No. 111,492

Term of patent 14 years

(Cl. D30—1)

To all whom it may concern:

Be it known that I, Norman W. La Clair, a citizen of the United States, residing at Forest Lake, county of Washington, and State of Minnesota, have invented a new, original, and ornamental Design for Projectile, of which the following is a specification, reference being had to the accompanying drawing, forming part thereof.

Figure 1 is a side elevational view of a projectile showing my new design;

Figure 2 is a top plan view of the same; and

Figure 3 is a bottom plan view of the same.

I claim:

The ornamental design for a projectile, as shown,

NORMAN W. LA CLAIR.
